UNITED STATES PATENT OFFICE.

MORGAN K. ARMSTRONG, OF WINNETKA, ILLINOIS, ASSIGNOR TO BESTWALL MANUFACTURING COMPANY, OF CHICAGO, ILLINOIS, A CORPORATION OF DELAWARE.

WEATHER-BOARD.

1,399,455.

Specification of Letters Patent. Patented Dec. 6, 1921.

Application filed February 24, 1920. Serial No. 361,021.

To all whom it may concern:

Be it known that I, MORGAN K. ARMSTRONG, a citizen of the United States, and a resident of Winnetka, county of Cook, and 5 State of Illinois, have invented certain new and useful Improvements in Weather-Board; and I do hereby declare that the following is a full, clear, and exact description thereof, reference being had to the accompanying drawings, and to the letters of reference marked thereon, which form a part 10 of this specification.

This invention relates to improvements in weather board and consists of the matters 15 hereinafter described and more particularly pointed out in the appended claim.

The object of the invention is to provide a corrugated, waterproof weather board for roofing, siding and the like.

20 The advantages of my improved weather board will more fully appear as I proceed with my specification.

In the drawings:—

Figure 1 is a perspective view of a piece 25 or section of weather board, embodying my invention.

Fig. 2 is an enlarged, transverse section through one margin of a piece or section of weather board embodying my invention and 30 having one form of bound edge.

Fig. 3 is a view similar to Fig. 2, and 35 illustrates another form of bound edge.

My improved weather board is made from a plaster board which consists of top and 40 bottom layers of fibrous material such as paper, and an intermediate core or body of plaster composition. This plaster board is preferably made by depositing upon a moving bottom layer or strip of paper, a suitable 45 amount or body of plastic composition, passing this strip of paper with the plastic composition upon it, between a pair of rolls, extending transversely to the movement of said bottom strip and simultaneously therewith, superposing a narrower top layer or strip of paper upon the top surface of the plastic composition, said top strip being fed about the top roll. The margins 50 of the bottom strip of paper, may during the manufacture thereof, be turned over and inwardly so as to overlap or underlap the margins of the bottom strip, there being a small amount of the plastic composition between the said margins of said strips, suffi-

cient to act as an adhesive or bond between them, thus providing a bound edge for the plastic board.

The paper covering used may be a waterproofed paper such as tar paper and the plastic composition may have a suitable asphaltum waterproofing solution incorporated therein, or the paper covering may be of plain rag pulp and the plastic composition may be free from asphaltum. With plaster board made as in the first instance, the same, while in a pliable condition, is passed through a suitable corrugating means and then allowed to harden or set, and in the case of a plaster board made of rag pulp paper that is not waterproofed, and a plastic composition that is not waterproofed, the same is passed through a suitable corrugating means and then allowed to set and harden after which the corrugated board is treated with asphaltum waterproofing solution by immersing the same in an asphaltum bath.

Referring now in detail to that embodiment of the invention illustrated in Figs. 1 and 2 of the accompanying drawings, 10 indicates as a whole, a piece of my improved corrugated weather board, which consists of opposed coverings of paper 11 and 12, and an intermediate plaster composition core or body 13, to which the coverings of paper 14 adhere. The margins 14 of the covering sheet 11, which is the bottom strip as it passes through the machine, and which preferably is that covering sheet faced outward and exposed to the weather when used, is folded in this instance, over and upon the margins 15 of the other covering sheet 12, a small amount 16 of the plastic composition acting to adhere the turned-over margins 14 of the strip 11 to the board as a whole. In Fig. 3 the margin 14^a of the sheet 11, is shown as folded over upon the plaster body and beneath the margin 15^a of the other covering sheet 12, a small amount of plastic composition 16^a acting to adhere the margins together. Thus a neatly bound edge is provided.

The corrugations are preferably, alternating undulations 17, as distinguished from alternating V-shaped or saw-toothed corrugations, said undulations extending longitudinally of the weather board, which of course is parallel with the bound edges

thereof. This form of corrugation in no manner breaks the fibrous coverings or injures the plaster body thereof, but acts to stiffen the board and insures against breakage or flattening of the board as a whole.

In applying the corrugated waterproofed weather boards in place, the margin of one board may be overlapped upon the margin of the adjacent board and the nails driven through the overlapping margins, all in the same manner as when applying corrugated iron for roofing or siding purposes. The improved corrugated weather board may be cut by means of the ordinary hand-saw, so that a perfect fit may be had about windows, doors and gables and it is waterproof and will readily take paint or stucco, so that the desired color effects may be obtained.

I claim as my invention:—

A weather board comprising top and bottom surface coverings of fibrous material, and a plaster composition body between and adhered to said surface coverings, said weather board being permeated with a waterproof solution and having longitudinally extending, alternately arranged undulations, and being of substantially the same thickness throughout its width.

In testimony that I claim the foregoing as my invention, I affix my signature in the presence of two witnesses, this 19th day of February, A. D. 1920.

MORGAN K. ARMSTRONG.
